United States Patent Office

Des. 183,532
Patented Sept. 16, 1958

183,532

COMBINED BEVERAGE MAKER AND DISPENSER

Raymond E. McCauley, Los Angeles, Calif.

Application October 21, 1957, Serial No. 48,180

Term of patent 14 years

(Cl. D2—3)

Figure 1 is a perspective view of a combined beverage maker and dispenser embodying my new design, the side thereof opposite that shown being the same in appearance as the side shown.

Fig. 2 is a side elevation thereof.

Fig. 3 is a front elevation thereof.

I claim:

The ornamental design for a combined beverage maker and dispenser as shown and described.
